J. J. Dally and Russell Mann, of Troy, N.Y.

Assignors to

George W. Eddy, of Waterford, N.Y.

Letters Patent No 920. Dated Aug. 4. 1857

The Schedule referred to in these Letters Patent and making part of the same.

To all whom it may concern.

Be it known that we J. J. Dally and Russell Mann, each of the City of Troy, in the County of Rensselaer, and State of New York, have jointly invented or produced a new and original Design for a Radiator Stove: and we do hereby declare that the following is a full and exact description of the same reference being had to the annexed photographic drawing making a part of this specification.

The hearth, A, of the stove is a circular plate, the ash box, B, and the fire-pot, C, united are in the form of a high bell, the mouth resting upon the hearth-plate: the lower portion, D, of the hot-air chamber on the fire pot has the form of an inverted bell, and its upper part, E, that of a saucer inverted over the mouth thereof: with a bell-mouth-shaped-pot-hole-cover F, (tipped with the scroll work G,) set upon its center.

The hearth-plate A, has a border moulding: the moulding B, along the bottom, the one C, along the top, and the ornamental figures D, along the middle, constitute the ornaments of the ash box: the fire pot C, is fluted in the manner shown;

That we claim as our invention or production and desire to secure by Letters Patent is

The ornamental design of the lower section of the stove, consisting of the parts A, B, and C, as herein described and shown in the annexed drawing.

And we also claim the external form or

DR

Wes. 920

configuration of the upper section of the stove consisting of the parts
A, M, D, and E, shaped as herein specified and shown in the drawing.
